CLAIM

The ornamental design for a ventilated cap, as shown and described.

DESCRIPTION

FIG. 1 is a right front top perspective view of the present design, a ventilated cap.

FIG. 2 is a right side elevation view of the present design, a ventilated cap; and,

FIG. 3 is a top plan view of the present design, a ventilated cap.

The left and right sides of the ventilated cap are mirror images of one another.

1 Claim, 3 Drawing Sheets

FIG. 1

FIG. 3
